146,649

DESIGN FOR A VANITY CASE OR SIMILAR ARTICLE

Richard T. Gaige, New York, N. Y., assignor to Volupte, Inc., New York, N. Y., a corporation of New York

Application May 10, 1946, Serial No. 129,545

Term of patent 7 years

(Cl. D86—10)

To all whom it may concern:

Be it known that I, Richard T. Gaige, a citizen of the United States, residing at New York city, in the county and State of New York, have invented a new, original, and ornamental Design for a Vanity Case or Similar Article, of which the following is a specification, reference being had to the accompanying drawing, forming a part thereof.

The figure is a perspective view of a vanity case or similar article, showing my new design.

The side not shown is substantially like the side shown.

I claim:

The ornamental design for a vanity case or similar article, substantially as shown and described.

RICHARD T. GAIGE.
